WALL MOUNTED DRINKING WATER DISPENSER

Ludwig Emde, Birmingham, and Herman B. Castillo, Clawson, Mich., assignors to Temprite Products Corporation, Birmingham, Mich., a corporation of Michigan

Continuation of design application Ser. No. 72,258, Oct. 25, 1962. This application Mar. 18, 1964, Ser. No. 79,139

Term of patent 14 years

(Cl. D67—4)

FIGURE 1 is a perspective view of a wall mounted drinking water dispenser embodying our new design.

FIGURE 2 is a front elevational view thereof; and

FIGURE 3 is a sectional view thereof taken along line 3—3 in FIGURE 1.

This application is a continuation of our copending application for design patent, Serial No. 72,258, filed October 25, 1962, now abandoned.

We claim:

The ornamental design for a wall mounted drinking water dispenser, as shown and described.
